UNITED STATES PATENT OFFICE.

JOHN C. SCHLEICHER, OF MOUNT VERNON, NEW YORK.

COMBINATION AMUSEMENT AND EDUCATIONAL BUILDING.

1,146,454.

Specification of Letters Patent.

Patented July 13, 1915.

Application filed February 5, 1914. Serial No. 816,807.

To all whom it may concern:

Be it known that I, JOHN C. SCHLEICHER, a citizen of the United States, residing at Mount Vernon, in the county of Westchester and State of New York, have invented certain new and useful Improvements in Combination Amusement and Educational Buildings; and I do declare the following to be a full, clear, and exact description of the invention, such as will enable others skilled in the art to which it appertains to make and use the same.

This invention relates to improvements in buildings and more particularly large public buildings arranged for accommodating large gatherings for amusement and educational purposes.

The main object of the invention is to provide a structure of this character of large capacity which may be effectively used during all seasons of the year for amusement and recreation purposes as well as for educational work.

Another object of the invention is to provide a building of this character having a circular auditorium with a central stage and effective means for ventilating the room and directing the sound waves outwardly from the stage to all parts of the room.

Another object of the invention is to provide a public building of this character having a large circular auditorium on its first floor with a series of stepped stories rising above the same and having surrounding balconies which communicate with separate towers or wings containing the elevator service, so that the building will be safe from dangers resulting from fire panics, since the persons in the building may readily pass from the immediate location of the fire to points of safety from which there will be ready escape.

Another object of the invention is to provide a building of the character referred to above which may have its auditorium used for vaudeville, moving picture shows, etc., while its upper floors may be used for exhibition purposes, dancing, billiard rooms and similar amusement and educational purposes; the building being also of such construction that it may be readily converted into a temporary school should it not be designed for such purpose when erected.

With the above and other objects in view, the invention consists of certain novel fea-

tures of construction, combination and arrangement of parts as will be more fully described and claimed.

In the accompanying drawings:—Figure 1 is a diagrammatic vertical sectional view through a circular building constructed in accordance with my invention; Fig. 2 is a detail sectional plan of portions of the circular movable stage; Fig. 3 is a sectional plan view of the circular auditorium; Figs. 4 and 5 are similar views taken on the planes indicated by the lines 4—4 and 5—5 in Fig. 1; Fig. 6 is a side elevation of the entire building on a reduced scale; Fig. 7 is a diagrammatic top plan view of the same; Fig. 8 is a partial elevation and vertical section through one of the wings at the front corners of the building; Fig. 9 is a similar view through one of the wings at the rear corners; and Fig. 10 is an enlarged detail sectional view showing the ventilating device.

Referring more particularly to the illustrated embodiment of my invention, 1 denotes the first floor or story of the building which is in the form of a circular auditorium having around its rear portion a balcony 2 which forms the second story or floor of the building. The latter may of course be of any size but I preferably make the building so that it occupies the usual city block or square bounded on three sides by streets and on the fourth side by an alley as indicated in Fig. 3. From the first and second stories at the two front corners project wings 3 which form entrances for the first floor of the auditorium and its balcony and on both floors of which there may be arranged ticket offices 4. On the two rear corners of the square are wings 5 which rise the full height of the building and have their upper portions connected by corridors or passage-ways 6 to the upper stories of the building which latter are of gradually decreasing diameter so that this portion of the building is of stepped formation as will be readily noted on reference to Figs. 1 and 9. On the wings 5 on one side are extensions 7 forming shafts for elevators 8 and on the other side of the wings 5 on the first and second stories are extensions 9 forming entrances for the two floors of the auditorium and containing ticket offices 10. In the wing 5 may be arranged smoke or ventilating flues 11, toilet rooms 12 and the like. It will be noted that these wings or towers 5 are separated from the

main portion of the building and connected thereto by the covered bridges or passageways 6 so that in case of fire in any portion of the main building the occupants of the 5 upper floors may readily pass to the wings 5 and descend in the elevators 8.

The entire building is to be made of fire-proof construction and as far as possible the 10 walls will be made of metal and have large windows to permit the entrance of plenty of sunlight and air so that the upper floors will be healthful and cheerful especially when they are to be used as class rooms as indicated at 13 in Fig. 5. The upper floors of 15 the building are divided by radial partitions 14 some of which may be composed of folding sections 15 so that adjacent segmental shaped rooms may be all thrown into communication. These partitions radiate from 20 an inner central wall 16 which forms on each floor an inner circular room 17 which may be used by the teachers or by the officers or attendants in charge of any exhibits or amusement devices which may be placed in the 25 different rooms on the upper floors. The inner rooms 17 communicate with each other by means of circular staircases 18 which wind around a centrally arranged air inlet pipe 19 which supplies fresh air to the auditorium as hereinafter explained. It will be 30 noted that all of the upper floors have surrounding balconies 20 on to which the occupants of the rooms may readily escape in case of fire and pass to the bridges or 35 corridors 6 and from thence to the towers or wings 5. These balconies are of fire-proof construction and project outwardly from the wall between each floor so that flames rising from the windows on one floor will not lick 40 up into the windows of the floor above. It will be further noted that the rail of each balcony lies within the vertical plane of the rail of the balcony beneath so that should any panic-stricken person jump over any 45 balcony, he would fall but the distance of one story. These balconies 20 not only serve as means for ready access to different rooms of the building and means to escape in case of fire, but they may be also used for recreation 50 purposes when the upper stories are used as school class rooms. The third floor has a balcony 21 of considerable width on which the children may play or which may be used as a promenade or for exercise by persons 55 using the building. The roof 22 is surrounded by a hand-rail and may be used as a play-ground by the children. If desired, the inner circular wall 16 of the top floor may be omitted as shown in Fig. 4 so that 60 this room may be used as a circular dancing hall, skating hall, dining hall, or play hall.

In the center of the circular auditorium is a circular stage composed of an outer annular stationary section 23 and a central

circular vertically movable section 24 which 65 may have a well or pit 25 for the musicians and may contain a piano 26 mounted on a pivot 27 so that it may be folded down into the pit to enable the latter to be closed by a cover thereby making the top of the entire circular stage 24 flat. The flooring of this stage is secured to a rectangular frame 28 of channel metal and from the four corners of this frame rise suitable hoisting cables 29 passing over suitable guides and 70 connected to a hoisting apparatus located at any desired point. These cables 29 are arranged adjacent four supporting columns 30 around which may pass a screen or curtain 31 having suitable means for raising 80 and lowering it. When this screen 31 is in position it will be noted on reference to Fig. 3 that four different motion picture exhibits may be projected on its four flat stretches and consequently a series of such shows may 85 be simultaneously operated in the auditorium. Of course the four sections of the auditorium may be separated from each other by screens or partitions so that different priced shows may be operated at the 90 same time but even though such separating screens are not provided in the aisles between the seats, a person occupying a seat in any one of the four quarters will have a good view of the picture projected on the screen 95 nearest to which he is located. In this connection it will be noted that when the building is used for school purposes and the upper floors used as class rooms, the auditorium may be used as an assembly room 100 and should there not be sufficient class rooms, portions of the sections of seats in the auditorium in the first floor and balcony may be separated by screens as indicated in dotted lines in Fig. 3 so that such inclosed 105 portions may be used as class rooms. Beneath the stationary circular stage 23 may be arranged dressing rooms, store rooms, etc., and all the apparatus used by the performers will be placed on the stage when it 110 is lowered into the basement.

For the purpose of providing effective ventilation for the auditorium and enabling the sound waves from the stage to be projected in all directions over the entire room, the ceiling 32 is inclined upwardly and outwardly from the center to the circular outer wall which latter has many windows or ventilating openings 33. The central air inlet flue or pipe 19 has a suction fan 34 arranged in it for drawing a large supply of air downwardly and projecting it against the upper side of a double, substantially cone-shaped deflector 35 arranged in spaced relation between circular plates 36-37. 120 The upper plate or flange 36 is inclined upwardly and outwardly and is placed on the central portion of the ceiling 33 around the 125

- open lower end of the pipe 19. The plate 37 is dished or cone-shaped and is connected to and spaced from the plate 36 by brackets 38. The deflecting plate 37 converges toward the plate 36 from its open central portion 39, outwardly and at the opening 39 there is a cone-shaped or funnel shaped sound collecting plate 40 disposed above the center of the stage and suitably connected to and supported by the plate 37. The double cone-shaped deflecting member 35 is suitably spaced between the plates 36-37 so that the sound waves rising from the stage will be collected by the plate 40 and directed upwardly and outwardly by the lower portion of the deflector 35 so that the fresh air being deflected outwardly by the upper portion of the deflector 35 will drive them outwardly to the distant portions of the rooms. It will also be noted that the heat rising from the room to the ceiling will be directed outwardly to the outlets 33 by the air currents.

From the foregoing description taken in connection with the drawings, it is believed that the many uses and advantages of the invention will be readily observed. A building of this construction may be used with comfort during all seasons of the year and it may be used by a large number of persons and hence the cost of maintenance may be reduced to the minimum and attractive shows provided for a small entrance fee. Because of its fire-proof construction and peculiar arrangement of parts it will be entirely safe in case of fire or panic for the reasons above given. The circular shape of the building gives it strength and also enables the occupants of the different portions to quickly and easily pass out since there are many exits and they radiate from the center. When the building is used as a school all of the classes may be accommodated in the auditorium or assembly room and after the morning exercises they may quickly pass to the different class rooms above and should the school be crowded, some classes may remain in the auditorium, portions of which may be screened off as intimated above.

Having thus described my invention, what I claim is:

1. A device of the character described comprising an air inlet pipe, a suction fan disposed therein, a sound collecting member operatively disposed contiguous to the lower end of said air inlet pipe, and means cooperating with the latter and said sound collecting member whereby the air flowing from said pipe and the sound waves from said sound collecting member may be simultaneously directed in an outward direction.

2. A device of the character described

comprising an air inlet pipe, a suction fan disposed therein, an outwardly projecting flange surrounding the lower end of said air inlet pipe, a deflecting plate depending from said flange in offset relation thereto, said plate having therein an opening registering with the open end of said air inlet pipe, a sound collecting member surrounding said opening, and projecting outwardly and downwardly therefrom, and means interposed between said plate and the open end of said air inlet pipe whereby air flowing from the latter and the sound waves from said sound collecting member may be simultaneously directed outwardly, substantially as and for the purpose set forth.

3. A device of the character described comprising an air inlet pipe, a suction fan disposed therein, an outwardly projecting flange surrounding the lower end of said air inlet pipe, a deflecting plate depending from said flange in offset relation thereto, said plate having therein an opening registering with the open end of said air inlet pipe, a sound collecting member surrounding said opening and projecting outwardly and downwardly therefrom, and a double deflecting member arranged in spaced relation between the lower end of said air inlet pipe and the opening in said deflecting plate, whereby air flowing from said air inlet pipe and the sound waves from said sound collecting member, may be simultaneously directed outwardly.

4. A device of the character described comprising an air inlet pipe, a suction fan disposed therein, an outwardly and upwardly projecting flange surrounding the lower end of said air inlet pipe, a deflecting plate secured in offset relation with respect to said flange, said plate having an opening therein registering with the open end of said air inlet pipe, a cone shaped sound collecting plate surrounding said opening and projecting outwardly and downwardly therefrom, and a double deflector arranged in spaced relation between the lower end of said inlet pipe and the opening in said deflecting plate, whereby the air flowing from the latter and the sound waves from said sound collecting member may be simultaneously directed outwardly.

5. A building having a circular auditorium with its ceiling inclined upwardly and outwardly, a central air inlet pipe extending downwardly through the center of the ceiling, a sound collecting member secured to said ceiling contiguous to said inlet pipe, and a deflecting member disposed intermediate said sound collecting member and said ceiling, whereby the air issuing from said inlet pipe and the sound waves from said sound collecting member may be simultaneously directed against said ceiling and

equally propagated in all directions by the latter, substantially as and for the purpose set forth.

6. A building having a circular auditorium with its ceiling inclined upwardly and outwardly, a central air inlet pipe extending downwardly through the center of the ceiling, a fan in said pipe for sucking the air downwardly, a sound collecting member secured to said ceiling contiguous to said inlet pipe, and a deflecting member disposed intermediate said sound collecting member and said ceiling, whereby the air issuing from said inlet pipe and the sound waves from said sound collecting member may be simultaneously directed against said ceiling and equally propagated in all directions by the latter, substantially as and for the purpose set forth.

7. A building having a circular auditorium with its ceiling inclined upwardly and outwardly and with its side wall having ventilating openings, a central air inlet pipe extending downwardly through the center of the ceiling, a fan in said pipe for sucking the air downwardly, a stage beneath said pipe, and means coöperating with said outwardly and upwardly inclined ceiling for simultaneously directing the air issuing from said pipe and sound waves disseminating from the stage against said ceiling, whereby they may be propagated equally in all directions from said air inlet pipe, substantially as and for the purpose set forth.

8. A building having a circular auditorium with its ceiling inclined upwardly and outwardly and with its side wall having ventilating openings, a central air inlet pipe extending downwardly through the center of the ceiling, a fan in said pipe for sucking the air downwardly, a stage beneath said pipe, a cone-shaped sound collecting member arranged above the stage and having a central opening, an inverted cone-shaped deflecting member surrounding said opening and inclined upwardly and outwardly toward the ceiling, but spaced therefrom, and a double deflector member arranged in spaced relation between the lower end of said air inlet and the opening in said cone-shaped sound collecting member for coöperation with the latter and said deflecting member to simultaneously direct the air issuing from said air inlet pipe and the sound disseminating from the stage against said ceiling and propagate the same equally in all directions, substantially as and for the purpose set forth.

9. A structure of the character described comprising an inclosure open at its upper end, a top for the open end of said inclosure, said top being inclined outwardly and upwardly from its central portion, a central air inlet pipe extending through the center

of said top, a sound collecting member secured in spaced relation to the under surface of the latter, contiguous to said air inlet pipe, an air deflecting member disposed intermediate said closure and sound collecting member, and means acting in conjunction with the former and the latter, to simultaneously direct the air issuing from said inlet pipe and the sound waves from said sound collecting member against the outwardly and upwardly inclined surface of said closure, whereby said air and sound waves are equally propagated in all directions, substantially as and for the purpose set forth.

10. A structure of the character described comprising an inclosure open at its upper end, a top for the open end of said inclosure, said top being inclined outwardly and upwardly from its central portion, a central air inlet pipe extending through the center of said top, a fan in said pipe for sucking the air downwardly, a sound collecting member secured in spaced relation to the under surface of the latter, contiguous to said air inlet pipe, an air deflecting member disposed intermediate said closure and sound collecting member, and means acting in conjunction with the former and the latter, to simultaneously direct the air issuing from said inlet pipe and the sound waves from said sound collecting member against the outwardly and upwardly inclined surface of said closure, whereby said air and sound waves are equally propagated in all directions, substantially as and for the purpose set forth.

11. A structure of the character described comprising a circular inclosure having its upper end open and its sides formed with openings contiguous to said upper end, a top disposed upon the open end of said inclosure, said top being inclined outwardly and upwardly from the central portion thereof, an air inlet pipe extending downwardly through the center of said top, a sound collecting member secured in offset relation to the under surface of said top contiguous to said air inlet pipe, an air deflecting plate disposed intermediate said sound collecting member and said top, and means acting in conjunction with said sound collecting member and deflecting plate to simultaneously direct the air issuing from said inlet pipe and the sound waves disseminating from said sound collecting member against said outwardly and upwardly inclined top, whereby said sound and air may be directed toward the openings in said inclosure, substantially as and for the purpose set forth.

12. A device of the character described comprising an air inlet pipe, a sound collecting member operatively disposed contiguous

to the lower end thereof, and means coöperating with the latter and said sound collecting member, whereby the air flowing from said pipe and the sound waves from said 5 sound collecting member may be simultaneously directed outward.

In testimony whereof I have hereunto set

my hand in presence of two subscribing witnesses.
